UNITED STATES PATENT OFFICE

WILLIAM A. GIBSON AND JAMES G. BURKE, OF ALLENTOWN, PENNSYLVANIA, AS
SIGNORS, BY MESNE ASSIGNMENTS, TO BRADLEY PULVERIZER COMPANY, A COR-
PORATION OF MASSACHUSETTS

ROLL-SUPPORTING CONSTRUCTION FOR CENTRIFUGAL GRINDING MILLS

Application filed October 24, 1924. Serial No. 745,574.

This invention relates to improvements in centrifugal grinding mills of the type in which the material is pulverized between a series of centrifugally actuated crushing rolls 5 and a co-operating annular die, and the general object of the invention is to provide a grinding mill of this character which is more simple and substantial in construction, more efficient and economical in operation, and in 10 which the wear and breakage of parts are reduced, and worn parts more economically replaceable.

The invention is disclosed herein as embodied in a grinding mill of the general type 15 illustrated in the following patents granted to the Bradley Pulverizer Company assignee respectively of Patent No. 1,175,436 E. C. Griffith March 14, 1916, and No. 1,473,341 Gibson and Needham November 6, 1923.

20 In mills of this type the centrifugally actuated crushing rolls are rotatably mounted upon the lower ends of shafts which are respectively secured in rocker heads which are pivotally mounted upon a rotatable carrier. 25 The rolls are provided with upwardly extending sleeves which embrace the shafts and bronze bushings are interposed between the rolls and their sleeves and the shafts. In such construction the rolls have to be accurately bored and the sleeves and bushings 30 accurately made. In the operation of the machine the rolls and the bushings are subject to high heat particularly when clinker and other hot materials are being ground.

35 One of the principal objects of the present invention is to provide a construction in which the rolls are rigidly secured to the lower ends of the roll shafts, the necessity for bushings between the roll and roll shaft 40 being thereby eliminated, thus reducing the cost of construction, assemblage and replacement of the rolls and avoiding the subjection of the bushings to the high heat in the grinding chamber.

45 A further object of the invention is to provide a construction in which the roll shafts are mounted in bearings in the rocker head located a sufficient distance apart to stabilize the shaft and reduce the vibration which results in crystallization of the shaft. This

is accomplished by providing the rocker head upper and lower bearings located respectively upon opposite sides of the pivotal support of the rocker head in the rotatable carrier and in extending the sleeve downwardly so that the lower bearing is preferably located in proximity to the roll, but above the highly heated zone of the die and co-operating roll.

55 A further object of the invention is to provide improved means for lubricating the bearings for the roll shaft. This is accomplished by providing a chamber in the sleeve of the rocker head which will receive a large quantity of lubricant and also providing sealing means at the bottom of the sleeve which will prevent the escape of lubricant therefrom so that the lubricant may be introduced under pressure at the upper end of the sleeve by a grease gun or other suitable 60 lubricant-forcing means.

65 A further object of the invention is to provide novel anti-friction bearing mechanism for the roll shaft including a thrust bearing for supporting the roll and its shaft.

70 Other objects and features of the invention will more fully appear from the following description and the accompanying drawings and will be pointed out in the claims.

75 In the drawings:

80 Fig. 1 is an elevation, partially in section, of a grinding mill of the type described, showing the embodiment of the invention therein; and,

85 Fig. 2 is a detail longitudinal sectional view through the rocker and its sleeve and through the grinding roll showing the roll shaft in elevation.

90 The mill illustrated in the accompanying drawings comprises a bed 1 having an upturned annular curb 2 forming a pan adapted to receive the material to be ground. The annular curb is provided with an upper detachable section 3 which co-operates with the lower section 2 to embrace and clamp therebetween an annular die 4. The base is provided with lateral extensions 5 to which are secured the lower ends of preferably A-shaped frames 6 having at their upper ends saddles 7 in which a girder 8, which extends dia- 95 100

metrically across the mill, is supported. This girder desirably is in the form of a slightly arched beam having a central preferably enlarged portion 9 having an aperture therethrough in which the central roll actuating shaft 10 is mounted. The roll actuating shaft 10 desirably is of tubular or quill shape and is rotatably mounted upon a solid shaft 11 which is rigidly secured at its bottom in a boss 12 projecting upwardly from the central portion of the base or pan 1.

The quill shaft 10 is connected at its upper end to and supported by a beveled gear 13 the hub of which is journaled in the central aperture in the beam 8. The beveled gear 13 is engaged and driven by a beveled pinion 14 upon a driving shaft 15 which may be actuated in any suitable manner. This construction may be and preferably is similar to that disclosed in Patent No. 1,473,341.

The quill shaft 10 has secured to it a rotatable carrier 16 generally circular in form and provided with an annular flange 17 which surrounds a stationary hopper member 18 into which the material to be ground is delivered. The base portion of the carrier is apertured and provided with tubular downwardly projecting extensions 19 to which inclined chutes 20 are attached which lead to the lower portion of the grinding chamber immediately in front of the crushing rolls. The carrier is also provided with extensions 21 which carry plows 22 projecting into the lower portion of the pan and which serves, during the rotation of the carrier to force the material in the pan into the path of the crushing rolls.

The carrier is provided with radially extending arms or yokes in which the trunnion shaft 23 is journaled in the usual manner.

The rocker head is in the form of a long sleeve 24 having a laterally extending boss 25 provided with an aperture to receive the trunnion shaft 23 and the outer wall of the boss desirably is split to provide sections 26 and 27 which may be drawn by a bolt 28 to clamp the sections of the boss firmly upon the trunnion shaft 23.

The sleeve 24 is provided near its upper end, preferably above the axis of the trunnion shaft, with an inwardly extending annular rib 29 presenting a flat shoulder 30 to support the thrust bearing which carries the roll shaft. The preferred form of roll shaft illustrated comprises a lower cylindrical portion 31 having a tapered lower end 32 upon which the roll 33 is fixedly secured by a nut 34 upon a screw threaded reduced end portion 35 of the roll shaft, the nut 34 being located in a countersink 36 in the roll. The peripheral portion of the nut 34 desirably is provided with a plurality of recesses 37 to receive a pin 38 which is driven into a suitable socket in the roll so that the nut is prevented from becoming unscrewed.

The roll shaft desirably is mounted in upper and lower anti-friction bearings in the sleeve of the rocker head which are located respectively above and below the horizontal plane of the axis of the trunnion shaft 23. Desirably the lower end of the sleeve extends into rather close proximity to the roll so that the upper and lower bearings are separated a considerable distance apart to stabilize the shaft, thereby preventing the vibration of the roll from causing crystallization of the shaft. The sleeve portion of the rocker head desirably is of considerably larger diameter than the roll shaft to provide a lubricant chamber and is provided at its lower end with an enlarged cylindrical chamber 39 in which an anti-friction bearing is mounted. In the embodiment of the invention illustrated the anti-friction bearing is in the form of a roller bearing the outer race 40 of which fits in the chamber 39 and the inner race 41 of which is secured upon a reduced portion of the roll shaft. One or more series of rollers 42 are interposed between the inner and outer races.

In order to prevent the escape of lubricant from the sleeve sealing means are provided at the lower end of the sleeve. Such sealing means illustrated herein comprise an annular collar 43 which fits upon the reduced portion of the roll shaft and has preferably a plurality of downwardly extending ribs 44 which intermesh with the grooves between complementary ribs 45 upon a sealing plate 46 which is bolted to the lower end of the sleeve 24.

The inner race 41 and the sleeve 43 upon the roll shaft are held in position by a nut 47 upon the roll shaft the lower face of which engages the upper end of the race 41 which at its lower end engages the collar 43 so that when the nut is set up the race 41 and collar 43 are clamped tightly against the shoulder formed by the junction of the reduced section of the shaft with the section 31 thereof.

The portion of the roll shaft which extends upwardly from the nut 47 is of slightly smaller diameter and the upper portion of the roll shaft is provided with a section 48 of still further reduced diameter which presents at its lower end a shoulder 49 to cooperate with a member of the thrust bearing. The thrust bearing comprises a cage having an annular wall 50 which fits within a cylindrical recess in the upper portion of the rocker head sleeve and rests at its lower end upon the shoulder 30 of the rib 29. A wear plate 51, which likewise rests upon the shoulder 30, supports a series of rollers 52 which engage a collar 53 located upon the reduced portion 48 of the shaft and which rests upon the shoulder 49 of the shaft. Another series of rollers 54 are interposed between the collar 53 and a hardened plate 55 which forms the top of the bearing cage. A collar 56 rests upon the plate 55 and is inter-

posed between the thrust bearing and the outer race 57 of the upper anti-friction bearing for the roll shaft. The inner race 58 of the upper bearing is spaced apart from the collar 53 upon the shaft by a sleeve 59. A 5 nut 60, upon the upper end of the shaft which engages the upper edge of the inner race, acts to clamp the inner race 58, the sleeve 59 and the collar 53 firmly against the shoulder 49 of the shaft.

10 A series of rollers 61 is interposed between the outer race 57 and the inner race 58. The outer race 57, the spacing sleeve 56 and the annular cage 50 with its upper wear plate 55 and lower wear plate 51 are clamped against the shoulder 30 of the sleeve 29 by a cap 62 which is secured to the upper end of the sleeve by machine bolts 63. By reason 15 of this construction it will be obvious that the roll is supported by the collar 53 and rollers 52 of the thrust bearing upon the wear plate 51 which rests upon the shoulder 30 of the rib 29 of the sleeve and that upward thrust is resisted by the thrust bearing as the shoulder 49 engages the collar 53 which in turn is engaged by the series of rollers 54 which act upon the wear plate 55 and which wear plate is held from upward movement by the spacing collar 56, the outer race 55 and the 20 cap 62.

25 Desirably means are provided for supplying lubricant under pressure to the chamber within the sleeve as the lower end of the sleeve is so sealed as to prevent escape of lubricant therefrom. As illustrated herein the means for receiving lubricant under pressure comprises an oil nut 64 which is secured in a suitable aperture in the cap 62. Of course, other forms of forced lubrication may be employed.

30 It will be obvious that the roll shaft and its anti-friction bearings can be readily assembled upon and removed from the sleeve and further that the bearings are so spaced apart as to give great stability to the shaft. The lower bearing is placed in as close proximity to the roll as is desirable, but is not within the roll itself and is not subject to the high heat which heretofore has been transmitted by conduction through the roll to the bearings when located within the roll.

35 By reason of the location of the bearings above and below the axis of the trunnion, detrimental action upon the bearings caused by the continuous vibration of the roll is wholly obviated or greatly lessened and oval wearing of the bearings prevented. In the present construction the roll when worn can be removed by merely withdrawing the pin 38, removing the nut 34 and driving the roll from the shaft and a new roll replaced. This permits a great saving in the cost of the rolls over previous constructions in which it is necessary to discard the bronze bushings as well as the worn roll.

40 The present construction permits the use

of roller bearings thus saving considerable power heretofore required to drive the rolls and the large lubricant chamber in the sleeve with its seal at its lower end permits the use of a superior type of lubrication over that which has been required in mills as heretofore constructed.

45 It will be obvious that the particular embodiment of the invention as disclosed herein is of an illustrative character and that various changes in form, construction and arrangement of parts may be made within the scope of the claims. It will be also obvious that the application of the invention is not confined to the particular form of mills disclosed herein, but may be embodied in any mill of the same general type within the scope 50 of the claims.

55 Having thus described the invention, what is claimed as new, and desired to be secured by Letters Patent, is:

1. In a centrifugal grinding mill of the class described comprising a roll shaft, a roll rigidly secured to the lower end thereof and a rocker head presenting a sleeve of greater internal diameter than the diameter of the roll shaft to receive the roll shaft, anti-friction bearings for said roll shaft within said sleeve adjacent to the ends thereof providing a lubricant chamber between said bearings and sealing means at the lower end of the sleeve for preventing the escape of lubricant comprising concentrically arranged members secured respectively to the sleeve and shaft having closely intermeshing complementary 60 annular ribs and grooves.

65 2. In a centrifugal grinding mill of the class described comprising a roll shaft having a roll rigidly secured to the lower end thereof, and having a reduced cylindrical portion presenting at its lower end a shoulder, a lower bearing race and a sealing member upon the reduced portion of said shaft, means for clamping the same against said shoulder, a rocker head presenting a long pivotally supported sleeve of greater internal diameter than the diameter of said roll shaft to receive said roll shaft and enclosing the reduced portion thereof, complementary lower bearing races surrounding said reduced portion of 70 said shaft, a series of rollers intermediate of said bearing races and complementary concentrically arranged sealing members secured respectively to said shaft and sleeve below said bearing races.

75 3. In a centrifugal grinding mill of the class described comprising a roll shaft having a roll rigidly secured to the lower end thereof, and having at its upper end a reduced cylindrical portion presenting a shoulder, a rocker head presenting an elongated sleeve to receive said roll shaft and provided with an internal rib presenting a shoulder located above the pivotal support of said rocker head, an anti-friction thrust bearing 80

for said shaft carried by said shoulder comprising a collar upon the reduced portion of said shaft and seated upon its shoulder, a roller bearing for said shaft located above said thrust bearing comprising an inner race on said reduced portion of the shaft and an outer race in said sleeve with rollers therebetween, a collar on said sleeve intermediate of said outer race and said thrust bearing, a cap on said sleeve clamping the outer race and collar upon the shoulder of the sleeve, a sleeve on said shaft intermediate of the inner race and the thrust bearing, a nut on said shaft clamping the inner bearing race and shoulder against the shoulder of the shaft, an anti-friction roller bearing intermediate of the lower portion of said sleeve and shaft and co-operating sealing members secured respectively to said shaft and sleeve having interengaging complementary ribs and grooves to prevent the escape of lubricant from said sleeve.

4. In a centrifugal grinding mill of the class described comprising a roll shaft having a roll detachably secured to the lower end thereof and having at its upper end a reduced cylindrical portion presenting a shoulder, a rocker head presenting an elongated sleeve of greater diameter than that of said shaft and provided near its upper end with an internal rib presenting a shoulder located above the pivotal support of said rocker head, a thrust bearing for said shaft comprising a bearing cage mounted upon the shoulder of said sleeve and having upper and lower wear plates, a collar on said shaft abutting the shoulder thereupon, upper and lower series of rollers located respectively intermediate of said collar and said upper and lower wear plates, means for clamping the bearing cage against the shoulder of the rocker sleeve, means on said shaft for clamping said collar against the shoulder of said shaft and anti-friction bearings for said shaft at the upper and lower ends of said rocker sleeve.

5. In a centrifugal grinding mill of the class described comprising a roll shaft having a roll detachably secured to the lower end thereof and having at its upper end a reduced cylindrical portion presenting a shoulder, a rocker head presenting an elongated sleeve of greater diameter than that of said shaft and provided near its upper end with an internal rib presenting a shoulder located above the pivotal support of said rocker head, a thrust bearing for said shaft comprising a bearing cage mounted upon the shoulder of said sleeve and having upper and lower wear plates, a collar on said shaft abutting the shoulder thereupon, upper and lower series of rollers located respectively intermediate of said collar and said upper and lower wear plates, an upper roller bearing for said shaft having inner and outer race-ways, a sleeve on said shaft between said inner race-way and

the collar on said shaft, a nut on said shaft engaging the upper end of said inner race and clamping the same, the sleeve therebelow and the collar against the shoulder upon said shaft and a cap on said sleeve engaging the upper end of the outer race-way acting to clamp said race-way and the thrust bearing race-way with the collar therebetween against the shoulder of the rocker sleeve and an anti-friction bearing for said shaft adjacent the lower end of said sleeve.

In testimony whereof, we have signed our names to this specification.

WILLIAM A. GIBSON.
JAMES G. BURKE.
